SHEET METAL LOCKING MEANS

Application filed May 15, 1929. Serial No. 363,318.

This invention relates to sheet metal locking means, that is, to means for joining or locking together a pair of sheet metal plates.

A further object of the invention is to include in the locking strip a body portion adapted to maintain the strip rigid whereby the same may be driven over the plate edges to effect the joint, and whereby the strip and therefore the plates will be reinforced along the joint effected.

The exact nature of the invention together with further objects and advantages thereof will be apparent from the following description taken in connection with the accompanying drawings in which Fig. 1 represents in elevation as from the exposed face, a pair of sheet metal plates arranged in joining relation, with the joint partially effected by the locking strip appearing, and Fig. 2 is a section transverse of the joint as in the plane of the line 2-2, Fig. 1.

In the drawings, 1 and 2 are the pair of sheet metal plates to be joined, and 3 represents generally the locking strip by which the joint is effected. The edge portions on the adjacent extremities of the plates are turned back as at 4 forming in section as shown Fig. 2, hooks, which hooks, of course, thus extend along the adjacent plate extremities. The plates are positioned as indicated with the bends 5 of their described turned-back edge portions, in abutting relation.

According to our invention we provide locking strip 3 for securing together the plates in this described relation. An essential feature of the locking strip is that it has the T-shaped slot indicated at 6 adapted to receive the turned-back edge portions 4 of the plates. To this end we preferably form the locking strip from a strip of sheet metal having a central body portion, with its edges bent toward each other and spaced from the body portion as at 7 to form therewith the slot 6. Thus the locking strip is generally of C section, and may be forced over the turned-back edge portions of the plates 1, 2 in the direction of the joint therebetween to lock the plates together.

The body portion of the locking strip, that

is, the central portion thereof between and maintaining the inwardly bent edges thereof, is folded upon itself as at 8 so that the locking strip has folds increasing the mass and thereby the strength of the body portion.

Thus, folds as shown Fig. 2 will maintain the strip 3 rigid so that the same may be driven over the edge portions of the plates to be joined, the section of the strip being sufficient to withstand hammer blows for the purpose and the body portion having sufficient stiffening ability to maintain the strip rigid while being driven. Likewise, the plates will be reinforced by said strip body portion, along the joint effected by the strip.

It will be observed that the outer fold 8 of the body portion of the strip overhangs the bent edge portions 4 which it overlies, so that the multiplicity of folds of the body portion will not be apparent in the finished joint.

Thus the plates at their joint may present a face interrupted only by an inconspicuous seam 9 along the abutting bends 5 of their turned-back edge portions.

The locking strip 3 will usually be as long as the joint to be effected. However, where clearance limitations are met with, the locking strip may be cut into sections, and the sections separately and successively driven. When it is desired to disjoin the plates the locking strip or strip sections may be removed by sliding from the plates in the direction of the joint.

What we claim is:

1. A locking device for joining the adjacent turned-back edge portions of a pair of sheet metal plates, comprising a sheet metal strip bent in folds providing a reinforced body portion having a plurality of thicknesses of the strip material, with its edges bent toward each other and spaced from said body portion to form therewith a slot of T-section to receive the turned-back edges of the plates to be joined, whereby to join the plates the locking strip may be driven without deformation over said plate edge portions in the direction of the joint, and the joint will be reinforced by said folds.

2. A locking device for joining the adja-

cent turned-back edge portions of a pair of sheet metal plates, comprising a sheet metal strip bent in folds providing a body portion of a plurality of thicknesses of the strip material, with its edges bent toward each other and spaced from said body portion to form therewith a slot of T-section to receive the turned-back edges of the plates to be joined, whereby to join the plates the locking strip may be driven without deformation over said plate edge portions in the direction of the joint, the outer fold of said body portion overhanging the bent edge portions which it overlies, so that the multiplicity of folds of said body portion will not be apparent in the finished joint.

In testimony whereof we hereby affix our signatures.

ROBERT F. CARPENTER.
THOMAS F. ANDERSON.
